US00D808773S

(12) **United States Design Patent** (10) Patent No.: **US D808,773 S**
(45) Date of Patent: ** Jan. 30, 2018

(54) **STRAP WITH HOOK AND LOOP CLOSURE FOR A CORD MANAGEMENT SYSTEM**

- (71) Applicant: **CJD LLC**, New York, NY (US)
(72) Inventors: **Wayne Philip Rothbaum**, New York, NY (US); **Allison S. Conner**, Brooklyn, NY (US); **Robert B. Curtis**, San Francisco, CA (US); **Jonas K. Damon**, New York, NY (US); **Daniel A. Sanchez**, Brooklyn, NY (US)
(73) Assignee: **CJD LLC**, New York, NY (US)
(***) Term: **15 Years**
(21) Appl. No.: **29/597,147**
(22) Filed: **Mar. 14, 2017**
